UNITED STATES PATENT OFFICE.

JOHN F. WING, OF MAYWOOD, ILLINOIS.

SPARK-GAP.

1,297,627.

Specification of Letters Patent. Patented Mar. 18, 1919.

Application filed September 1, 1916. Serial No. 117,979.

To all whom it may concern:

Be it known that I, JOHN F. WING, a citizen of the United States, residing at Maywood, in the county of Cook and State of Illinois, have invented certain new and useful Improvements in Spark-Gaps, of which the following is a specification.

My invention relates to improvements in spark gap devices, and refers particularly to devices for intensifying igniting sparks for explosive engines.

Among the more salient objects of the invention, are to provide a device that will greatly increase the strength of the spark; to provide a device that will at all times produce a spark in the engine cylinder in spite of the fact that the spark plug may be defective; to provide a device that will have the minimum of parts; to provide a device of material that will enable an observer to see if the spark is actually present at any time; to provide an improved method of securing the metal cap to the body of the device; to provide a device that can be easily, quickly and securely attached to an ordinary spark plug of an explosive engine; to provide a device that is simple and one which can be cheaply made; and, in general, to provide an improved device of the character specified.

In the accompanying drawings,—

Figure 1 is a view, showing the device attached to an ordinary spark plug;

Fig. 2 is an enlarged central vertical section of the device;

Fig. 3 is a view of the right hand end with the plug removed; and,

Fig. 4 is a view of the glass body part or barrel.

Referring to the drawings, 11 is a fragmentary part of a cylinder head, into which is placed a spark plug 12 of any well known make and having a thumb nut 13, by means of which a terminal clip is held on the spark plug. The above parts are of well known construction, and as they form no part of the present invention, need no further description.

The invention consists of a device indicated generally at 14 in Fig. 1. It is made up of a body portion or barrel of cast glass 15. The purpose of this glass is not only to act as a perfect non-conductor, but it also permits the determining of whether the spark is in operation. The barrel has a central opening 16 therethrough and has a bulg-

ing side portion and enlarged end portions 17. This shape provides a neck portion 18 of slightly smaller diameter than the flange and bulging portions. The inner edges of the end portions or flanges have small triangular shaped indents 19. These are spaced throughout the circumference of the flange parts 17 and there may be any number of them.

On the outer faces of these flanges at either end are caps 20, which are internally threaded centrally so as to furnish nipples 21. These nipples are integral with the cap. At one end of the glass barrel adjacent to the nipple opening is a circumferential opening 22, in which is placed a washer or gasket 23 of rubber or other similar material. Between the cap and the flange portion of the barrel at either end is placed a paper or other air tight cushion 24. When the combined cap and nipple is placed on the ends of the glass barrel the ends 25 of caps 20 project slightly beyond the inner edges of the flanges 17. The metal of the ends 25 of the caps is then crimped or bent inwardly until a sufficient quantity of the metal enters the indents 19. This permanently secures the caps in place and effectually prevents the said caps from being rotated or removed from the glass barrel.

Threaded into the nipple at the left hand end, or spark plug end of the device, is a plug 26. This plug has an enlarged flange 27 and a terminal clip 28. The flange 27 is slightly larger in diameter than the opening 22 so that when the compressible gasket 23, which is a trifle thicker than the depth of the opening, is placed therein the flange must compress said gasket to permit the flange to seat itself on the cap. At the other end of the device there is provided a similar plug 29. The usual terminal clip 30 on the end of the high tension cable is secured between nuts 31 and 32. The outer nut must be loosened to permit the removal of the clip 30. At the inner end of the plug 29 is provided a sparking point 33, which permits the current to jump to plug 26 and then to the spark plug.

From the foregoing description it will be evident that the current from the magneto or spark coil flows through the terminal clip 30 to the plug 29 and to the sparking point 33, thence to the plug 26 and to the terminal clip 28. From the clip 28 it flows to the spark plug 12 and into the engine cylinder.

It will be obvious that the details of construction may be varied more or less without departing from the scope of the invention, and I do not wish to be limited to the details of construction except as set forth in the broader of the appended claims.

What I claim is:

1. In a spark gap, a body portion of insulating material, caps at the ends of said body portion, said body portion having notches adapted to receive portions of the caps for securing the caps against displacement, nipples formed integral with said caps, and terminal clips connected to said nipples.
2. In a spark gap apparatus, a body portion of insulating material, metal caps adapted to be held on the ends of said body portion, said caps having their inner ends bent inwardly, said body portion having notches into which the metal is forced, and air tight cushions between said body portion and said caps.
3. In a spark gap device, an insulating body portion, cup shaped caps for the ends of said body portion, the body portion having notches for receiving portions of the cap, nipples formed integral with said caps, terminal clip plugs adapted to be threaded in said nipples, and gaskets between said body portion and said caps and surrounding said nipples.
4. In a device of the class described, a cylindrical body portion of glass, flanges formed at the ends of said body portion, notches formed in the flanges adjacent to said body portion, cup shaped caps for the flanges of said body portion, said caps

adapted to have a portion thereof bent into said notches to hold the caps against displacement on said flanges, and sealing means between said caps and said body portion.

5. In a device of the class described, a cylindrical body portion of insulating material, having notches formed in the ends thereof, caps having portions bent into said notches, integral nipples in said caps, terminal members adapted to be secured in said nipples, paper washers between said body portion and said caps, and a resilient gasket disposed between one of said terminal members and one of said nipples.

6. In a device of the class described, a cylindrical glass body part having an opening therethrough, flange portions at either end of said body part, indents being formed in said flange portions adjacent said body part, cup shaped caps for said flange portions, said cup shaped caps having the extreme ends of their flanges adapted for bending inwardly so that the bent metal thereof may enter the indents in the body portion, internal nipples formed integral with said caps, said nipples adapted to project into the opening in the body part, one of said caps having a depression adjacent said nipple at one end of said body part, a compressible washer for said depressed portion, cushions of air tight material between said caps and said body part, and terminal plugs threaded into the nipples at either end, and terminal clips connected to said plugs.

JOHN F. WING.
